UNITED STATES PATENT OFFICE.

FRANK A. EPPS, OF NEW YORK, N. Y., ASSIGNOR, BY MESNE ASSIGNMENTS, TO
FOAMITE FIREFOAM COMPANY, OF NEW YORK, N. Y., A CORPORATION OF
DELAWARE.

ART OF EXTINGUISHING FIRES.

1,355,951.

Specification of Letters Patent. Patented Oct. 19, 1920.

Original application filed January 9, 1917, Serial No. 141,374. Divided and this application filed May 3, 1918. Serial No. 232,291.

To all whom it may concern:

Be it known that I, FRANK A. EPPS, a citizen of the United States, residing at New York, in the county of New York and State 5 of New York, have invented new and useful Improvements in the Art of Extinguishing Fires, of which the following is a specification.

This invention relates to improvements in 10 the art of extinguishing fire, and pertains more particularly to processes operating under foam-extinguishing principles, being a division of my application filed Jan. 9, 1917, Ser. No. 141,374, Patent No. 1,296,937, 15 dated March 11, 1919.

Operations under foam-extinguishing principles involve the formation of what may be termed an "aqueous blanket," this blanket, when complete, overlying the burning 20 surface and serving to extinguish the fire. The blanket is the result of bringing into commixed relation two component solutions normally retained separate, these solutions, when brought together, providing 25 chemical reactions for the production of the foam form of the content. The efficiency of the blanket is, of course, more or less dependent upon the character of the foam formation, as well as its lasting qualities, 30 these factors being important in determining the efficiency of the fire-extinguishing medium. And one of the determining factors in this connection is the limiting characteristic of length of life of the bubble 35 formation.

The object of the present invention is to provide for the production of an "aqueous blanket" of maximum life by bringing the foam formation to maximum development 40 with rapidity and placing the formation in the "aqueous blanket" form with rapidity after its formation, thus having the major portion of the life of the bubble formation active in the blanket form. This result may 45 be obtained in various ways, the preferred method, however, being to bring the two solution streams into commixing relation at the point of application by delivering the streams in directions to oppose each other 50 and forcibly break down the stream formations and substantially overcome the stream pressures, thus bringing the solution contents into intimate commixture and enabling the chemical reactions of the components to

be rapidly developed into the foam condition, the foam formation then being delivered on to the surface to be acted upon. 55

The streams are delivered in opposite or opposing directions, but it is to be understood that these terms are not limited to a 60 strict construction, since the relative positions of the outlet ends of the solution-conveying pipes may be otherwise than in direct opposition, these terms being satisfied by an arrangement in which the streams 65 pass into contact after being discharged and forcibly break down the stream formation sufficiently to provide for the development of the foam after being discharged.

To these and other ends, therefore, the 70 nature of which will be readily understood as the invention is hereinafter disclosed, said invention consists in the improved methods hereinafter fully described, illustrated in the accompanying drawings, and more particularly pointed out in the appended claims. 75

In the accompanying drawings, in which similar reference characters indicate similar parts in each of the views:—

Figure 1 is a view in elevation showing a 80 simple form of structure applicable to the outlet ends of solution discharge conduits and adapted to carry the invention into practice.

Fig. 2 is a longitudinal sectional view 85 taken on line 2—2 of Fig. 1.

Fig. 3 is a top plan view of the structure of Fig. 1.

Fig. 4 is a view partly in section and partly in elevation showing one way in 90 which the structure of Fig. 1 may be employed in connection with an oil tank.

Fig. 5 is a sectional view taken on line 5—5 of Fig. 4.

In the drawings I have shown simply the 95 delivery portion of an apparatus, the invention being adapted to be used with any type of storage and conduit structures for the separate solutions, it being understood, of course, that the actual delivery of the individual solutions from the conduits when the latter are opened for service, will be under pressure so as to provide for solution discharge under pressure conditions.

The form of apparatus employed for illustrating the invention provides for discharge 100 of the solution streams in direct opposition to each other, the several streams being de-

livered under pressure, thus meeting "head-on" at a point intermediate the outlets, the stream formations thus being forcibly broken down and the delivery pressure substantially overcome.

In the form shown, 10 and 10^a indicate two conduits adapted to deliver the several solutions to heads 11 and 11^a respectively, these heads being removably secured to the 10 conduits and shown as extending in axial alignment, with the outer ends of the heads opposite and spaced from each other, each head being normally closed by a suitable cap 12, the arrangement placing the heads as 15 the terminal ends of the respective conduits.

Caps 12 are normally held seated by a suitable retaining means, this being shown as in the form of a toggle structure 13 formed of two members which are normally held in 20 cap-retaining position by a fusible element or structure indicated as a plate or plates 14. This toggle structure is illustrative and is of a type in which a spring 15 is housed between the members for the purpose of aiding 25 to break the toggle when the fusible element is made inactive in the presence of fire conditions, thus not only permitting the solution pressure on the caps to be made effective in breaking the toggle, but also utilizing 30 the power of the spring to provide this result so that the caps are rapidly freed from the retaining effect of the toggle and thus rapidly release the streams from the respective outlets. As it is desirable that the 35 arrangement employed be such as to enable a new retaining device to be placed in position when desired, I have shown heads 11 as carried by U-shaped mating members 16 which are joined together by bolts 17, thus 40 retaining the parts in proper alignment for effective operation, and yet permitting ready removal of parts to restore the apparatus to working condition, the U-shaped members confronting each other to provide an open 45 space therein within which the retaining device extends.

The method may be employed in any desired relation, it being especially applicable for use in connection with the protection of 50 tanks for inflammable materials, this use being indicated in Figs. 4 and 5. The particular manner of mounting the apparatus for practising the method may vary, a simple and efficient manner of mounting being 55 shown in the drawings wherein conduits 10 and 10^a are led into the wall of the tank—the latter being indicated at T—near the top, thus locating the outlet ends of the conduits permanently within the tank and above 60 the normal level of the contents, the retaining device being thus located in favorable position for action on the fusible element 14 under fire conditions. And I also prefer to employ a shield 18, which may be 65 of semi-circular configuration as in Fig. 5,

the shield tending to isolate the space within which the ends of the conduits extend and restrict any tendency of the contacting stream splattering the contents except as may be permitted by the shield. The shield 70 preferably omits any bottom for the space, so that the space within the shield is permanently open to the tank from below, thereby enabling rapid development of the conditions which bring about the release of the 75 retaining device, and at the same time permitting the free movement of the foam formation downwardly on to the top surface of the tank contents, there being practically no liability of so choking up this space as 80 might tend to affect the production of the foam when caps 12 are released. This shield, however, is not absolutely essential.

As will be readily understood, the retaining device will retain caps 12 in position to 85 close the outlet ends of the respective conduits, whether the contents of the conduits be under pressure or not while the apparatus is set ready for operation whenever fire conditions require. When fire conditions are 90 present and the fusible element 14 becomes so affected as to release the toggle members, the latter will be automatically thrown aside by the action of spring 15 and the discharging pressure of the conduit contents, this 95 latter being made active if the contents are not normally under pressure, the caps also being thrown aside by the pressure. This release of the caps immediately renders both outlets free to discharge the contents of the 100 respective conduits, so that each solution is discharged from its conduit in stream form and directly toward the stream discharging from the opposite outlet, these streams, discharging under pressure, meeting "head-on" 105 within the space between the two outlets, with the result that each stream will be forcibly broken down by the action of the other stream, both streams thus being broken down and concurrently overcoming the discharging pressure. Since the components of 110 the two streams are such as to provide for chemical reaction when brought together, the forcible break down or more or less disintegration of the stream form produces a 115 condition especially favorable to rapid commixing of the components and setting up the chemical reactions with rapidity, thereby producing the foam formation which is free to move down through the space and 120 the open lower end of the shield directly on to the surface upon which the blanket is to be formed.

It will therefore be seen that by this particular method, I am able to locate the point 125 of foam production directly at the point of application, so that while the method permits of rapid development of the foam condition, this development takes place so close to the surface to be acted upon that no ma- 130

terial loss in the active life of the bubble formation is had, the result being that substantially the entire active life of the bubble formation is made available. In addition, 5 the space within which the foam formation is produced is sufficiently large so as to take care of the normal expansion produced when the streams are changed into the foam formation, so that there is no material pres-

10 sure present on the bubble formation during travel through and out of this space, practically maintaining the integrity of the bubble formation through the absence of any physical deteriorating means.

15 As will be understood, the structures shown in the drawings are more or less illustrative of ways in which the invention may be carried out, it being understood that various ways of providing this result can be 20 employed.

While I have herein shown and described a way in which the invention may be carried into practice, it will be readily understood that changes and modifications 25 therein may be found desirable or necessary in meeting the exigencies of use, and I desire to be understood as reserving the right to make any and all such changes or modifications as may be found desirable or essential, 30 in so far as the same may fall within the spirit and scope of the invention as expressed in the accompanying claims when broadly construed.

What I claim is:

35 1. In fire-extinguishing systems of the foam-extinguishing type and wherein the component solutions are normally maintained separate and are brought into commixing relation at the point of application and under fire conditions, the method of producing the solution commixture which consists in locating the solution discharge ports substantially at the point of application, the ports being adapted to discharge the solutions in stream form, normally restraining the solutions against discharge, and 40 currently releasing the solution streams from confinement and under pressure in the presence of fire conditions, the direction of flow of the discharging streams

causing the streams to oppose each other to forcibly break down the stream formations and substantially overcome the stream pressures, whereby reaction of the component elements of the commixed and broken-down 55 streams is rapidly developed, the zone of forcible contact between said streams being located in an open space free from said solutions.

2. In fire-extinguishing systems of the 60 foam-extinguishing type, the method of admixing the solutions at a delivery terminal, which consists in maintaining the individuality of the solution streams during travel to such terminal, and releasing such streams 65 in stream form and under pressure substantially at the point of application and under fire conditions, with the flow path of one released stream intersecting the similar path of the other stream to cause the streams to 70 forcibly contact and commix at such point of intersection, whereby the stream form of the solutions will be destroyed in the formation of an aqueous blanket, the zone of forcible contact between said streams being located in an open space free from said solutions. 75

3. The process of producing a fire-extinguishing medium of the "aqueous blanket" type, which consists in normally maintaining component solutions of the blanket separate, producing flow of the separate solutions in stream form when the blanket is to be produced, and producing the blanket by delivering the several streams in steam form 80 at the point of application in intersecting flow paths and into forcible contact to cause concurrent disintegration of the stream form and commixture of the stream contents, the zone of forcible contact between 85 said streams being located in an open space free from said solutions.

In testimony whereof I have hereunto set my hand in presence of two subscribing witnesses.
